DE LOS N. HICOK, OF NEWARK, NEW JERSEY, ASSIGNOR TO FEDERATED ENGINEERS DEVELOPMENT CORPORATION, OF JERSEY CITY, NEW JERSEY, A CORPORATION OF DELAWARE.

FUSIBLE ELEMENT.

Application filed August 17, 1922. Serial No. 582,564.

This invention relates to improvements in fusible elements such as the temperature sensitive element commonly used to control sprinkler systems or similar devices.

5 In order to more fully understand the objects of the present invention, it will be necessary to point out certain of the defects of the fusible elements or links now commonly employed which consist of various metallic 10 alloys. In the first place, a fusible alloy to melt at a definite temperature throughout its entire mass must be what is commonly known as eutectic. This corresponds with a definite but not usually with a simple proportion of 15 the metals. Owing to the oxidation and drossing of these metals during the process of alloying, it is hard to hold even a binary alloy to a definite composition and almost impossible to keep a ternary or quaternary alloy 20 homogeneous and of definite proportion.

As a consequence, these fusible alloys are not reliable. While the eutectic alloys will theoretically melt at a definite temperature, as a matter of fact the commercial alloys 25 vary from the eutectic and are liable to melt as much as 10° F. above or below the theoretical temperature; again the remelting of the alloys in casting will often make a radical change in the composition and a serious 30 variation in the melting point.

Furthermore, fusible metallic alloys have virtually no power of resisting a prolonged stress. They are more or less ductile or plastic even at ordinary temperatures and 35 if subjected to loads of pressure or tension, even if the loads are light, will, in the course of time, flow or yield to the load even while cold. In other words, all these alloys are in reality viscous fluids even at normal 40 temperatures and their fluidity or plasticity increases greatly as they are heated. They become so soft at temperatures far below their melting point, that when a power transmitting element is connected to them, they 45 will gradually yield, twist or stretch and eventually rupture at temperatures widely variant from their calculated melting or yielding point.

Furthermore, fusible alloys are limited to 50 a few eutectic alloys of narrow temperature

range. They are subject to corrosion by certain chemicals and fumes such as nitric and chlorine, and cease to function when so attacked.

I am aware that other fusible substances 55 besides metallic alloys have been employed as fusible elements, such as paraffine, resin, sealing wax, pitch, etc. Such substances are very unsatisfactory for the reason that they are very plastic when heated and will yield 60 at temperatures that are far below their melting points.

An object of the present invention is to provide a fusible element which will remain solid and unyielding even when heated up 65 to a temperature closely approaching its melting point; in other words, to provide an element whose elastic limit is close to its rupture point even when heated approximately to its melting point so that the element will not yield until it ruptures or is about to rupture; or in still other words, to employ an element that does not pass through a wide range of plasticity as its temperature is raised to its melting point. 75 Another object is to provide an element capable of withstanding tension, compression or torsion and an element whose melting point or point of release will be absolutely definite within 1° or at the most 2° F. 80

In other words, I propose to supplant the metallic alloys and other fusible materials heretofore used, all of which are more or less ductile or plastic even at temperatures far below their melting points and which 85 will flow and stretch readily as they approach within ten or fifteen degrees Fahrenheit of their melting point, by a homogeneous crystalline substance which is non-plastic and which remains unyielding until 90 it is heated to a certain temperature when it will suddenly liquefy or rupture.

It is a further object of this invention to supply fusible elements that may be used at temperatures below those possible with 95 fusible alloys, such as freezing mixtures; also to cover a wider range of temperature than is possible to do with fusible alloys.

It is yet another object of this invention to suggest certain constructions of links or 100

certain combinations of my fusible elements with a surrounding or supporting container which may have various uses.

With these and other objects in view, the invention consists in certain novel features of construction and combinations and arrangement of parts as will be more fully hereinafter described and pointed out in the claims.

10 In the accompanying drawings,

Figure 1 is a somewhat diagrammatic sectional view illustrating the type of link or fusible element which I prefer to employ under tension.

15 Figure 2 is a similar view illustrating a modified form of link diagrammatically shown as under compression.

Figure 3 illustrates another modification wherein a fusible element adapted to withstand torsional strain is shown.

20 It is to be understood that the drawings accompanying this specification are purely illustrative and that an infinite number of expedients might be resorted to for carrying 25 out the invention in other ways. Both the uses of the element and the forms which it may take are practically unlimited.

Pure stable chemical compounds of crystalline character having definite melting 30 points have proven to be most satisfactory for fulfilling the objects hereinbefore stated. An organic compound is preferred, preferably but not necessarily, an organic salt. The nature of the compound depends ob- 35 viously upon the use to which it is to be put, since compounds having the necessary requirements may be utilized for different purposes because of the difference in their melting points. Alpha-mono-nitronaphtha- 40 lene, for instance, will be found desirable for indicating temperatures of approximately 120° F. Dichlorobenzene, diphenylamine and various other pure chemical compounds may be used when a different melting point is 45 desired.

It is a well known fact that many pure stable chemical compounds of crystalline character, have an elastic limit near their point of rupture, will melt throughout their 50 mass within 1° or 2° of temperature, and being of a fixed definite composition will melt and solidify an indefinite number of times without change of character.

It is also a well known fact that many 55 such compounds are known that heretofore have found little commercial application. Again the melting point of a compound may be changed by the addition of one or more radicals, the substitution of one or more 60 radicals or change in orientation of one or more radicals. Furthermore, the resistance to corrosion, solution, etc. may be changed by similar processes.

It is a purpose of this invention to utilize

these characteristics of pure stable chemical 65 compounds as a means of obtaining fusible elements, that will cover wide ranges of temperatures, that will be reliable and permanent, and can be adjusted to resist specific causes of corrosion and deterioration.

70 It has been heretofore suggested that suitable substances might be found for withstanding the action of acid fumes. In the event that a link is to be used in an atmosphere containing chlorine gas, a link of some 75 substance such as dichlorobenzene might be used. Cobalt nitrate or dinitrobenzene would serve a similar purpose in the event 80 that nitric acid was in the air. Still another method of accomplishing the same result would be to coat the entire link by dipping 85 in a chemical compound resistant to specific surroundings. This construction serves to provide a protecting coating of another pure stable chemical compound of a higher melting point to resist the action of the surrounding medium. Links of different types would of course be used to resist the action of different gases, acids, alkalis and chemicals.

90 Referring with particularity to Figure 1 of the drawings, I have used the reference numeral 1 to indicate a cup-like container into which a pre-heated pure chemical compound 7 may be poured in a liquid state. As the compound solidifies, it serves to embed 95 within itself one end of a link 2 of a chain. An inturned lip 3 at the upper end of the cup-like container prevents the entire body 100 of compound from being pulled out of its casing when tension is exerted on the chain 4 of which the link 2 forms a part. I have designated a contraction spring 5 acting to tension the chain and have shown the container 1 as formed with a depending apertured lug 6 receptive of a chain link. With 105 this form of device, the chemical compound will melt or release whenever the temperature of the heat conducting casing 1 reaches the necessary point. The compound, however, is absolutely prohibitive of any yielding or stretching of the chain prior to the 110 time such temperature is reached.

115 Referring in detail to Figure 2 of the drawings, I have illustrated a container 10 adapted to seat on a supporting base 11. A connecting rod 12 has one end embedded 120 in the chemical compound 13 with which the container 10 is filled. An expansion spring 15 is indicated interposed between a suitable support 16 and a ring 17 on the connecting rod. This drawing is merely illustrative 125 of the fact that a chemical compound such as set forth in the claims will not yield under compression prior to reaching its melting point or point of release.

In the modified form of device shown in Figure 3, a casing 20 for the fusible material 21 is formed with a stuffing box 22 in

its upper end, said stuffing box providing a bearing for one end of a vertically disposed shaft 24. The spring 25 acting on the flexible device 26 tends to turn the shaft 5 through the medium of a pulley wheel 28 on the upper end of said shaft. Radially disposed blades or paddles 29 secured to the shaft and embedded in the compound serve to absolutely prevent any turning movement 10 of the shaft independent of the container.

As soon as the temperature of the compound reaches the necessary point, the same will liquefy permitting turning of the pulley and revolution of the paddle blades. 15 This form of the invention is not only useful in retaining a mechanical device against premature operation, but may be used conversely to stop its operation whenever the temperature of the compound becomes sufficiently 20 low to solidify the same. In cases, for instance, where it is desirable to maintain a boiling mixture at a pre-determined point, the paddle blades would be suddenly stopped, their stoppage acting to operate a signal 25 in any approved manner to indicate a falling temperature.

To sum up, it will be seen that I provide a link or similar fusible device comprising a container adapted to be filled with a chemical 30 compound. A mechanical device embedded in the compound and placed under tension, compression or torsion will be held against motion as long as the compound remains in a solid state. When the temperature 35 of the material surrounding the compound rises sufficiently to cause melting of the compound, said mechanical device is released and set in motion. The device may be used to indicate temperature, to operate 40 a signal, to open or close a valve, empty or fill a tank, or in other ways too numerous to mention.

It will be understood that the word "element" as used in the foregoing specification 45 and the appended claims is to be interpreted not in its technical chemical sense but in its general sense as meaning an essential part, body, member or substance.

I have illustrated certain of the preferred 50 embodiments of the invention and have specified a few stable chemical compounds suitable for the purpose of carrying it out, but it will be evident that I do not wish to be limited to any class of compounds, except as defined in the appended claims.

I claim:

1. As a new article of manufacture, a temperature sensitive device comprising a liquid container adapted to receive a fusible 60 substance in liquid state, a fusible substance therein consisting of a stable organic compound of crystalline character, and a stressed element anchored in the compound.

2. As a new article of manufacture, a temperature sensitive device comprising a 65

liquid container adapted to receive a fusible substance in liquid state, a fusible substance therein consisting of a stable organic salt, and a stressed element anchored in the compound. 70

3. As a new article of manufacture, a temperature sensitive device comprising a liquid container adapted to receive a fusible substance in a liquid state, a fusible substance therein consisting of a stable chemical 75 compound of crystalline character, and a potential element anchored in said compound.

4. As a new article of manufacture, a temperature sensitive device comprising a liquid container adapted to receive a fusible substance in a liquid state, a fusible substance therein consisting of a stable chemical 80 compound of definite melting point, and a stressed element anchored in said compound. 85

5. As a new article of manufacture, a temperature sensitive device comprising a liquid container adapted to receive a fusible substance in a liquid state, a fusible substance therein consisting of a stable chemical 90 compound having its rupture point and elastic limit approximately co-incident, and a potential element anchored in said compound. 95

6. As a new article of manufacture, a temperature sensitive device, including a stressed fusible element consisting of a chemical compound that remains non-plastic at temperatures below and up to the fusion point. 100

7. A temperature sensitive device comprising a pair of relatively stressed members and a body of fusible material serving while solid, to hold said members against relative movement, said body consisting of a stable 105 chemical compound of crystalline character.

8. A temperature sensitive device comprising a pair of relatively stressed members and a body of fusible material serving while solid, to hold said members against relative 110 movement, said body consisting of a stable organic salt.

9. A temperature sensitive device comprising a pair of relatively stressed members and a body of fusible material serving while 115 solid, to hold said members against relative movement, said body consisting of a stable chemical compound of definite melting point.

10. A temperature sensitive device comprising a pair of relatively stressed members and a body of fusible material serving while solid, to hold said members against relative movement, said body consisting of a substance that remains non-ductile at temperatures below and up to its fusing point. 120

11. A temperature sensitive device comprising a pair of relatively stressed members and a body of fusible material serving while solid, to hold said members against relative 125 movement, said body consisting of a substance that remains non-ductile at temperatures below and up to its fusing point. 130

movement, said body consisting of a substance that remains non-plastic at temperatures below and up to its fusing point.

12. A temperature sensitive device comprising a pair of relatively stressed members and a body of fusible material serving while solid, to hold said members against relative movement, said body consisting of a substance having its rupture point and elastic limit approximately co-incidental at temperatures below and up to the immediate vicinity of its fusion point.

13. A temperature sensitive device comprising a pair of relatively stressed members and a body of fusible material serving while solid, to hold said members against relative

movement, said body consisting of a stable chemical compound of crystalline character having its rupture point and elastic limit approximately co-incidental at temperatures 20 below and up to the immediate vicinity of its fusion point.

14. A temperature sensitive device comprising a pair of relatively stressed members and a body of fusible material serving while 25 solid, to hold said members against relative movement, said body consisting of a stable organic salt having its rupture point and elastic limit approximately co-incidental at temperatures below and up to the immediate 30 vicinity of its fusion point.
